J. FRITSCHE,
CHECK CONTROLLED VENDING MACHINE,
APPLICATION FILED JUNE 10, 1916.

1,222,859.

Patented Apr. 17, 1917.

UNITED STATES PATENT OFFICE.

JOHN FRITSCHÉ, OF PHILADELPHIA, PENNSYLVANIA.

CHECK-CONTROLLED VENDING-MACHINE.

1,222,859.

Specification of Letters Patent. Patented Apr. 17, 1917.

Application filed June 10, 1916. Serial No. 102,847.

To all whom it may concern:

Be it known that I, JOHN FRITSCHÉ, a citizen of the United States, residing in the city and county of Philadelphia, State of Pennsylvania, have invented a new and useful Check-Controlled Vending-Machine, of which the following is a specification.

In hotels, restaurants, and places of a similar character, considerable expense has heretofore arisen due to the loss of towels, and it is one purpose of my present invention to devise a novel construction of a vending machine, preferably check or coin controlled, whereby upon the insertion into the machine of a check or coin of the proper denomination, one is enabled to withdraw a clean towel from the machine, but is prevented from taking it away with him.

A further purpose of my invention is to devise a novel construction of a locking mechanism, whereby when the mechanism is unlocked, an article can be withdrawn and during its withdrawal, effect the relocking of the locking mechanism.

With the above and other objects in view which will hereinafter appear more clearly in the detailed description, my invention consists of a novel construction and arrangement of a check-controlled vending machine, wherein upon the payment of a coin of the proper denomination, an article can be withdrawn for temporary use, but cannot be disconnected from the machine and taken away.

It further consists of a novel construction and arrangement of a casing, a novel construction and arrangement of a guide and support for the articles to be vended, a novel construction of a locking mechanism,—novel means for effecting the relocking of such mechanism as an article is withdrawn from the machine, and novel means for preventing the withdrawal of an article from the casing without being paid for.

Other novel features of construction and advantage will hereinafter more fully appear in the detailed description of my invention.

For the purpose of illustrating my invention, I have shown in the accompanying drawings a typical embodiment thereof, which in practice will give satisfactory and reliable results, but it is of course to be understood that this embodiment is typical

only, and that the various instrumentalities of which my invention consists can be variously arranged and organized, and that my invention is not limited to the precise arrangement and organization of these instrumentalities as herein shown and described.

Figure 1 represents a perspective view of a check-controlled vending machine, embodying my invention.

Fig. 2 represents a section on line 2—2 of Fig. 3.

Fig. 3 represents a sectional view on line 3—3 of Fig. 6.

Fig. 4 represents a vertical section of a portion of the coin slot.

Fig. 5 represents a front elevation of a portion of Fig. 6.

Fig. 6 represents a section on line 6—6 of Fig. 3.

Fig. 7 represents a sectional view, on an enlarged scale, of a portion of the locking member seen in Figs. 2, 3 and 6.

Fig. 8 represents in perspective, a portion of an article and a grasping member therefor.

Fig. 9 represents a sectional view on line 9—9 of Fig. 1.

Similar numerals of reference indicate corresponding parts in the figures.

Referring to the drawings:—

1 designates a casing of a check-controlled vending machine embodying my invention, and the contour and dimensions of such casing may vary widely in practice in accordance with the requirements and conditions under which the machine is to be used.

For purpose of illustration, I have shown the casing as being rectangular in form and provided with a front wall 2, a rear wall 3, side members 4, a bottom 5, and a top 6. In order to provide access to the interior of the casing, in order to fill the machine or to remove articles therefrom, one wall of the casing is hinged, as for example, the rear wall 3 as at 7. 8 designates a tubular rod or sleeve secured to the bottom 5 in any desired manner and adapted to receive one vertical extension of a guide rod 9, which telescopes thereinto and is secured therein by means of a fastening device 10 of any desired character.

11 designates an intermediate wall or partition which divides the casing 1 into two compartments 12 and 13, respectively. The

guide rod 9 extends above the casing at its central portion and is preferably curved and is provided with a vertical extension which is located in the compartment 13, and its 5 free end is received in a socket 14 of any desired character.

My present machine is especially adapted for controlling the withdrawal from the machine of articles 15, such as for example, 10 towels or other articles of a sheet formation or of a foldable nature. The articles 15 are preferably provided with reinforcing eyelets 16, thereby adapting them to be assembled on the sleeve 8. In connection with these 15 articles, I preferably employ a grasping member 17 which is manually held by the operator. One form of such member is illustrated in Fig. 8, as consisting of a strip of material bent upon itself and having the 20 free ends offset, as at 18, and provided with the apertured flanges 19, the apertures of which are adapted to register with the eyelets 16 so that each article is provided with a grasping member, whereby it may be 25 raised from the compartment 12, as will be hereinafter described.

The grasping member 17 preferably has the side walls parallel so that it is guided between the guide plates 20 and 21 which are 30 located in the compartment 12 in the present instance. The guide plate 20 is provided with an aperture 22 and the guide plate 21 is provided with a similar aperture 23 located in alignment with the aperture 22 and 35 into said apertures a locking member 24 is adapted to extend. This locking member 24 consists of a bolt or bar, which is longitudinally slidable in the apertured brackets or guides 25 and 26, respectively, which are 40 carried by the wall or plate 55 of the casing. The bottom face of the locking member 24 near its rear end is laterally recessed, as at 27, thereby forming a shoulder 28, which at certain periods of the operation interlocks 45 with the bracket 26. The locking member 24 is provided intermediate its ends with a slot 29, into which is adapted to extend one end of a locking lever 30, which is pivotally supported at 31. The forward end of the 50 lever 30 is adapted to pass into the apertures 32 and 33 of the guide plates 20 and 21, respectively, so as to extend through the slot formed by such guide plates.

The rear end of the locking member 24 is 55 provided with a coin-retaining device 34 comprising a coin chute having its longitudinal axis inclined relative to the longitudinal axis of the locking member 24, and provided at its upper end with a laterally extending 60 ledge 35 forming an abutment for the coin. A portion of the rear face of the coin retainer 34 is outwardly deflected to form a loop 36, to which one end of a spring 37 is secured, the other end of said spring being 65 secured to any suitable fixed portion of the

casing. The lower end of the coin chute 34 is slotted, as at 54, in order that the cam member 38 may freely pass therethrough when no coin is present in the coin retainer 34. The cam member 38 is mounted on a 70 rock shaft 39, which extends through the front wall of the casing and is provided with a grasping handle 40 of any desired construction.

The shaft 39 is rotatably mounted in a 75 bracket 41 carried by the casing. 42 designates a spring, one end of which is connected to the cam member 38 and the other end of which is connected to a fixed portion of the casing. 43 designates an arm secured to the 80 locking member 24 and adapted to travel in the path of the lower end of the pivoted side member 44 of the coin chute 45, which extends through the front end of the casing, as indicated at 46. A pivot pin 47 of the pivoted member 44 is outwardly and laterally deflected in order to adapt it to receive one end of a spring 48, the other end of which is connected with a stud 49. The top 6 of the casing is provided with an opening 50 (see 90 Fig. 1) which communicates with the compartment 12. This opening is normally closed by means of a door 51 which is provided with a depending stop member 52 which tends to close said slot on the opening 95 of the door 51. In other words, a double door is provided, as will be hereinafter explained. The top member 6 is also provided with a spring pressed door 53 which opens inwardly and leads to the compartment 13. 100

The operation of my novel vending mechanism will now be apparent to those skilled in this art, and is as follows:

The articles are first placed in the compartment 12 and are strung on the sleeve 8, 105 the grasping member being preferably employed having a bifurcated end, into which the article passes. The casing of the machine is then closed and the articles are ready for delivery. The intending user or purchaser places a check or coin of the proper denomination in the coin slot 46, and the coin passes through the chute 45, and assuming that the parts are in the position indicated in Fig. 4, the coin passes through the 110 coin chute and drops into the coin retainer 34, the parts being in the position seen in Fig. 2, the lower end of the coin resting on the cam member 38. The purchaser now turns the handle 40 in a clockwise direction, thereby causing the coin or check to be moved upwardly against the ledge 35 of the coin retainer and causing the rear end of the locking member 24 to be raised until the shoulder 28 becomes disengaged from the 115 bracket 26, whereupon the spring 37 causes the locking member 24 to be moved into the position seen in Fig. 6.

The purchaser now takes hold of the uppermost grasping member 17 and moves it 120

upwardly in the slot formed by the guide plates 20 and 21. This causes such grasping member to engage the inclined or cam face end of the lever 30 thereby causing the locking member 24 to move forwardly until the shoulder 28 interlocks with the bracket or guide 26. Since this locking member moves forwardly as soon as the uppermost grasping member passes the forward end of the locking member, it will be seen that but one article can be removed at a time. The article is guided on the sleeve 8 and as it engages the door 51, the door moves outwardly in the direction of the arrow seen in Fig. 9 and is retained on the guide member 9 exterior of the casing, so that the towel, for example, is ready for temporary use. The depending arm 52, as the article is being withdrawn through the opening 50, will move inwardly so as to prevent any one from fraudulently obtaining the use of an article by attempting to insert his hand through such opening. After the article has been used, it slides on the rod 9 and drops through the opening controlled by the inwardly opening door 53, so that a soiled article, such as a towel, will be received in the compartment 13. As the locking member 24 moves forwardly, the arm 43 engages the lower end of the pivoted member 44 of the coin chute 45, and causes it to be moved into its open position, as seen in Fig. 4, so that it is ready for the reception of another coin or check. The spring 48 maintains its pivoted member 44 in its open or closed position, it being seen that if the locking mechanism is in its unlocked position, the passage of the coin through the coin chute 45 will cause the upper end of the pivoted member 44 to move inwardly so that if a check or coin is inserted into the machine when it is in this condition, the upper end of the pivoted member 44 causes the check or coin to be ejected from the coin chute 45, so that the machine will not operate.

After the articles have been removed from the compartment 12, the door, such as 3, is unlocked and opened, the fastening device 10 is loosened, and the guide and retainer device is removed, whereupon the articles which have been used can be moved from the machine and a fresh supply of articles placed in the compartment 12.

It will be apparent from the foregoing that in accordance with my present invention, I have devised novel means for locking the articles in place within the casing and for permitting the removal of an article for temporary use, only when a check or coin of the proper denomination has been inserted into the machine.

It will be apparent that by dispensing with the free end of the guide and retainer 9 which extends into the compartment 13, that the articles may be vended in

such a manner that the purchaser can take them away with him, if he so desires.

When no coin is in the machine, the cam member 38 can freely pass through the slot 54 of the coin retainer. The check or coin serves as an interlocking device to effect the interlocking of the cam member 38 with the locking member 24 and its adjuncts.

It will be seen that I provide means to automatically effect the relocking of the locking mechanism during the withdrawal of an article from the compartment 12.

It will now be apparent that I have devised a novel and useful check-controlled vending machine, which embodies the features of advantage enumerated as desirable in the statement of the invention and the above description, and while I have, in the present instance, shown and described a typical embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A device of the character stated, comprising an article receiving casing, an article guide within the casing and extending exterior therefrom, a grasping member for each article to effect its removal, locking mechanism controlling the withdrawal of an article, and means in the path of a grasping member and actuated by it as an article is withdrawn from the casing to automatically effect the relocking of said locking mechanism.

2. A device of the character stated, comprising a casing having a plurality of compartments, an article guide fixed in said compartments and extending exterior of the casing, a grasping member for each article to effect its removal, locking mechanism controlling the withdrawal of an article, and means in the path of a grasping member and actuated by it as an article is withdrawn from the casing to automatically effect the relocking of said locking mechanism.

3. A device of the character stated, comprising a casing having a plurality of compartments, and openings thereinto, doors for said openings, an article guide fixed in said compartments and having a portion extending exterior of the casing in proximity to said doors, a grasping member for each article to effect its removal, locking mechanism controlling the withdrawal of an article, and means in the path of a grasping member and actuated by it as an article is withdrawn from the casing to automatically effect the relocking of said locking mechanism.

4. A device of the character stated, comprising a casing, an article guide connected with the casing and extending exterior thereof, a grasping member for each article to effect its removal from the casing and slidably on said article guide, locking mechanism for said grasping members, and means in the path of a grasping member and actuated by it as an article is withdrawn from the casing to unlock said locking mechanism.

5. A device of the character stated, comprising a casing, a retaining device within the casing and extending therefrom, means connected with said retaining device to effect the removal of an article from the casing, locking mechanism for said article removing means, means to lock said mechanism as an article is removed from the casing, and means to effect the unlocking of said mechanism.

6. A device of the character stated, comprising a casing having a plurality of compartments and provided with openings communicating with said compartments, a guide and retaining device extending into each compartment and through said openings and having a portion exterior of the casing, article removing means operatively connected with said device, locking mechanism for said article retaining means, means to unlock said locking mechanism, and means to automatically effect the relocking of said mechanism as an article is removed from the casing.

7. A device of the character stated, comprising an article receiving casing, means to effect the removal of an article for temporary use only, locking mechanism for said removal means, and means in the path of said article removing means and actuated by such means to automatically effect the relocking of said mechanism.

8. A device of the character stated, comprising a casing, article removing means guided in the casing to cause an article to be temporarily retained exterior of the casing, locking mechanism to prevent the removal of said article removing means, and means controlled by said article removing means during its movement to effect the relocking of said locking mechanism.

9. A device of the character stated, comprising an article receiving casing having an opening through which the articles are removed, a retaining device with which the articles are assembled and extending exterior of the casing, a door controlling said opening, a grasping member for each article to effect its removal, a locking bolt preventing, when in locked position, the removal of said articles, a tension device for said locking bolt, means to secure said locking bolt in its forward position, and means in the

path of an article being removed to cause 65 the relocking of said bolt.

10. A device of the character stated, comprising a casing to receive the articles, a retaining device on which the articles are strung, located within the casing and extending exterior thereof, a locking bolt to prevent removal of said articles, manually controlled means to effect the unlocking of said bolt, and means in the path of an article being removed from the casing to effect the 75 relocking of said bolt.

11. A device of the character stated, comprising an article receiving casing, an article retaining device within the casing and extending exterior thereof, a locking bolt slidably mounted and preventing the removal of articles from said casing, manually controlled means to effect the unlocking of said locking bolt, and a fulcrum lever in the path of an article being removed from said casing 85 and provided with an arm engaging said bolt to move it into locked position as an article is being withdrawn.

12. A device of the character stated, comprising a casing, an article retainer on which 90 the articles are carried, located within the casing and extending exterior thereof, a locking bolt slidably mounted to prevent articles from being removed from the casing, a tension device to maintain said bolt 95 in locked condition, a rock shaft, a cam member thereon, said cam member and said lock bolt being adapted to be interlocked by a coin or check to effect the unlocking of said bolt on the rotation of said shaft, and 100 means to maintain said shaft in normal position.

13. A device of the character stated, comprising a casing, an article retainer on which the articles are carried, located within the casing and extending exterior thereof, a locking bolt slidably mounted to prevent articles from being removed from the casing, a tension device to maintain said bolt 110 in locked condition, a rock shaft, a cam member thereon, said cam member and said lock bolt being adapted to be interlocked by a coin to effect the unlocking of said bolt on the rotation of said shaft, means to maintain said shaft in normal position, and a 115 lever pivotally supported and having one end extending in the path of an article being removed and having its other end adapted to engage said lock bolt to effect the relocking of said bolt as an article is withdrawn from the casing.

14. A device of the character stated, comprising a casing having a plurality of compartments, an article retaining device extending into said compartments and having a portion exterior of the casing and on which the articles are secured, means to pass 125 an article from said casing, a lock bolt slid-

ably mounted and having a recess forming a shoulder, a guide to interlock with said shoulder, a tension device for said lock bolt to maintain it in unlocked position, a manually operated cam member, a retainer carried by said lock bolt, said retainer being adapted to be interlocked with said cam member by a coin or check to effect the un- locking of said lock bolt, and means controlled by an article being removed to effect 10 the locking of said lock bolt.
